UNITED STATES PATENT OFFICE.

LESTER E. HICKOK, OF CLEVELAND, OHIO, ASSIGNOR OF ONE-HALF TO THE CLEVELAND HARDWARE COMPANY, OF CLEVELAND, OHIO.

VEHICLE-GEAR.

974,142.

Specification of Letters Patent.

Patented Nov. 1, 1910.

Application filed October 2, 1909. Serial No. 520,639.

To all whom it may concern:

Be it known that I, LESTER E. HICKOK, a citizen of the United States, residing at Cleveland, in the county of Cuyahoga and 5 State of Ohio, have invented certain new and useful Improvements in Vehicle-Gears, of which the following is a specification.

Heretofore, vehicle gear irons, or parts, adapted for use in connection with an axle, head block and a single reach, have been forged separately and attached to the reach, head block and axle when the constituent parts of the vehicle running gear were assembled at the shop or manufactory. In 15 practice much time has been consumed and difficulty experienced in correctly assembling and fitting the numerous parts of the gear, due in a measure to the fact that each part must occupy a proper and determinate 20 position relative to each other part, and such relative disposition of them is usually effected only after successive adjustments and readjustments. By reason of the irregular shapes and the necessary relative 25 locations of parts they cannot be forged integral except by an excessive expenditure of time and at a cost prohibitive of their sale. Now, I have devised a way of obviating the difficulties attending the assembling 30 and fitting of the parts at the shop, and the forming of certain parts and elements integrally.

My invention consists in forging the reach iron, head block plate, and upper member of 35 the fifth wheel separately and then rigidly uniting them in their proper relative positions by rivets or by projecting lugs formed on some parts which enter holes in other parts and are upset.

40 The accompanying drawing illustrates one example of the physical embodiment of my invention and a modification of the single reach iron constructed according to the best modes I have so far devised for the 45 practical application of the principle.

Figure 1 is a view in perspective of parts of a single reach or perch vehicle gear, some of which are united together rigidly, and disclosing my invention. Fig. 2 is a view of 50 the single reach iron detached or as it is forged. Fig. 3 is an enlarged section on line $x-x$ Fig. 1. Fig. 4 is a part section on line $y-y$ showing the means for attaching the reach iron to the upper fifth wheel.

member. Fig. 5 is a view in perspective of 55 a modified form of a single reach iron.

Referring to the figures, the letter A designates the perforated reach; B, a single reach iron with holes at one end and a plate C at the other end, said plate having a concave seat D, and perforated lugs E at the sides to receive the threaded ends of clips in the well-known way; F, the head block plate which fits within the seat D of the plate at the end of the reach iron; G, the lower member of the fifth wheel; H, the upper or top member of the fifth wheel; I, the king bolt brace having in this instance two holes at its rear end; J, the reach strap; K, a bolt which is passed through the front hole in 70 the end of the reach iron and the hole at the end of the reach strap; L and M, bolts passed through holes in the reach iron, reach, reach strap, and king bolt brace, and all said bolts provided with nuts which 75 serve to clamp the several parts together; N, an anti-rattler; and O, in Fig. 5, a single reach iron having two forks each of which is provided with a seat for the head block plate and two holes for the threaded ends 80 of clips.

I have devised a way to rigidly unite the reach iron to the head block plate and also to the upper fifth wheel member. Upon the top surface of the plate C of the reach 85 iron are lugs or projections P P, which enter holes through the head block plate, said projections P extending slightly above the top surface of the head block plate, and the holes Q being reamed out or enlarged at R 90 as shown. By upsetting or displacing the metal of the projections or riveting them down the reach iron and head block plate are rigidly united in fixed relative positions.

The central portion of the metal of the 95 reach iron is offset as shown to form a seat S for the top member of the fifth wheel, and a downward projection T may be forged to the shape indicated though in some cases it may be omitted entirely. A hole U is 100 made through the off-set portion of the metal, which hole is enlarged at the top end. A similar hole V is made through the top fifth wheel member in line with the hole U which hole is enlarged at the lower end. A 105 rivet W is then inserted in the holes and its ends upset and the heads countersunk as clearly shown in Fig. 4.

A modified form of single reach iron shown in Fig. 5 is attached to the upper fifth wheel member and the head block plate as above described, the projections P at the 5 ends of the block being similar to those shown upon the plate of the previously described reach iron. Separable or partly integral rivets or projections upon one member adapted to enter holes in the other member 10 or analogous means may be employed to rigidly unite the separately forged parts.

It is obvious that when united the top 15 fifth wheel member and the head block plate occupy fixed positions relative to the reach iron and that the whole may be regarded and handled as a unit when being secured to the reach and head block plate, and the 20 adjustments and re-adjustments incident to the handling and fitting of the independent parts separately be obviated.

What I claim is:

1. The combination with a head block plate, and an upper fifth wheel member, of a single reach iron centrally disposed relative to said head block plate and upper fifth wheel member, said parts being separately forged, and metallic means with the metal upset rigidly uniting the reach iron to the upper fifth wheel member and the head 25 block plate.

2. The combination with a head block plate, and an upper fifth wheel member, of a single reach iron centrally disposed relative to the head block plate and upper fifth 35 wheel member, said parts being separately forged, and means consisting of lugs and rivets rigidly uniting the front end of the reach iron to the head block plate and the part of the reach iron intermediate its ends 40 to the upper fifth wheel member.

3. The combination with an upper fifth wheel member, of a head block plate, a single reach iron said iron being centrally disposed relative to the upper fifth wheel member and its front end provided with 45 means for attachment to the head block plate, said parts being separately forged,

and metallic means with the metal upset rigidly uniting the reach iron to the upper fifth wheel member.

50

4. The combination with an upper fifth wheel member, of a head block plate, a single reach iron said iron being centrally disposed relative to the upper fifth wheel member and its front end provided with means for 55 attachment to the head block plate, said parts being separately forged, and a rivet rigidly uniting the reach iron to the upper fifth wheel member.

5. The combination with an upper fifth 60 wheel member, of a single reach iron having a seat at its under surface to receive the upper fifth wheel member, said reach iron being centrally disposed relative to the upper fifth wheel member, and means in 65 connection with the seat rigidly uniting the reach iron to the upper fifth wheel member.

6. The combination with a head block plate, of a reach iron having its front portion located beneath and fitting the head 70 block plate, and metallic means passed from one member into the other and upset, rigidly uniting the said two elements.

7. The combination with a single centrally disposed reach iron having the metal offset 75 or forged to form a seat at its under surface, of an upper fifth wheel member with its central part fitting the seat; and means rigidly uniting the reach iron and upper fifth wheel member at their contact surfaces. 80

8. The combination in a vehicle gear, of a single centrally disposed reach iron having the metal intermediate its ends offset or fashioned to form a seat at its under surface; a reach; a reach strap; and a fifth 85 wheel member located within the opening formed by the offset portion of the reach iron and the reach strap.

In testimony whereof I affix my signature in presence of two witnesses.

LESTER E. HICKOK.
